UNITED STATES PATENT OFFICE.

JAMES T. HOYT, OF NEW YORK, N. Y.

CABINET OR PAPER-CASE.

SPECIFICATION forming part of Letters Patent No. 588,066, dated August 10, 1897.

Application filed September 17, 1896. Serial No. 606,169. (No model.)

To all whom it may concern:

Be it known that I, JAMES T. HOYT, a citizen of the United States, residing at New York, in the county and State of New York, have 5 invented new and useful Improvements in Cabinets or Paper-Cases, of which the following is a specification.

By means of this invention a cabinet or case can be made of simple or cheap construction and easy of operation, as also capable of holding a considerable supply of paper or sheets; and the invention resides in the novel features of construction set forth in the following specification and claims and illustrated in the annexed drawings, in which—

Figure 1 is an elevation of the cabinet, showing its front or discharging wall. Fig. 2 is a section along $x-x$, Fig. 1. Fig. 3 is a section along $y-y$, Fig. 1. Fig. 4 is a side elevation of a modification. Fig. 5 is a sectional view of Fig. 4. Fig. 6 is a sectional side elevation of another modification.

The cabinet or case comprises the sides 1, bottom 2, top 3, and back 4. The sides have 25 tracks, ways, or grooves 5 for guiding the movable or sliding front or discharging wall. By having the front flexible to fold or slide about within the limits of the sides 1 the device will not require excessive room for its 30 operation. The front is shown composed of strips or sections 6, joined by a flexible backing 7. The front carries a wider strip or section 8, having a discharge-slit 9 for the delivery of sheets of paper and a finger-opening 35 10, giving access to roller 11 12 for actuating the latter to start the discharge of a sheet.

The sheets or paper-pack 13 has a bottom or support 14 and a fastening or retaining strip or band 15, on which the sheets are 40 strung or which passes through perforations near the rear edge of the sheets. The bottom or support 14 has a hook or catch 16, made to engage a lip 17 on a support or slide 18. When the back 4 is removed, the support 18 45 can be slid out of or into the case along the cleats or ways 19, which hold the support 18 somewhat clear of the case-bottom 2. When the support 18 with supply 13 is in place in the case, the strip or band 15 can be secured 50 or looped to a cross-piece or holder 20, secured in the case. By making the retaining-strip 15 of thin or sheet metal and suitably slotting

the cross-piece 20 the strip 15 can be inserted into the slot in the cross-piece and then suitably bent over, so that the upper or free end 55 of the strip will not accidentally come loose.

The roller 11 12 by having the portion 12 corrugated will offer a suitable contact-surface for the finger inserted through opening 10 to rotate the roller. The roller portions 60 11, if roughened or sanded, will enable the roller when suitably rotated to feed the sheets through the discharge 9.

The roller 11 12 is journaled in arms or bearings 21, carried by the front part or section 8, and as the pile of sheets 13 diminishes the front 6 8 slides in guides 5 to allow the roller 11 12 to sink lower, so as to come into contact with the sheet which is at the top of the pile. The discharge-opening 9 by this 70 movement of the front is kept in alinement with or in discharging position for the top sheet.

The axle of the roller 11 12 is shown guided by grooves or ways 22 in the case sides, and 75 these grooves also form stops preventing excessive motion of the roller and of the case-front in an upward or downward direction. The support 18 being supported clear of the case-bottom 2 the lower edge of the front 6 8c can slip back into the case between said support and bottom.

As a considerable space in the case can be made to receive paper, the supply of the latter can be correspondingly large.

The movement of the front 6 to keep the roller 11 12 moving to or in contact with the paper-supply can be effected in any suitable way, as by suitably weighting the roller or making the roller or contiguous parts so heavy 90 as to automatically move and keep the roller in contact with the gradually-diminishing pile of sheets.

The top 3 and back 4 are shown removable, the back 4 when removed clearing the way 95 for the removal of top 3. When in place, the back 4 can be locked by suitable means. The removal of back 4 and top 3 gives access to the interior of the case for supplying the latter with paper or for fastening the same in 100 place or for other purposes. The case is shown as secured by one of its sides to a wall or support 23.

Instead of being turned through finger-

opening 10 the roller might have its shaft extended through a slot 22', Fig. 4, in a side 1, said extended shaft portion having a button, knob, or handle 24 for rotating. In place of 5 only one roll 11 12 a pair or several rolls, one behind the other, can be applied, as known.

The condition or amount of supply in the case can be readily determined from the exterior without opening the case, since the location or elevation of the opening 10 or knob 24 or a sight through the opening 10 will, for example, indicate whether the contents are exhausted or so nearly so as to make recharging advisable or necessary. It will thus be 15 seen that the opening 10 or knob 24 acts as an indicator for determining the amount of supply in the case.

The holder 15 instead of being arranged as in Fig. 2 might be otherwise arranged—as, for 20 example, in Fig. 6, where a holder 15' is carried by or moves with the wall 6 8 and pierces or engages the sheets or some of the upper sheets to prevent the roller 11 12 from feeding more than one sheet at a time.

25 Any suitable guard, (not shown,) as well known in the art, can be applied to prevent the leading edge of a sheet passing up between the front 8 and roller 11 12, whereby blocking of the passage is obviated.

30 It will be observed that the roller is carried by the front and is adapted to turn, but this roller is not translatable independently of the front—that is to say, the center or axis of the

roller cannot be displaced or moved unless the front is also moved or slid.

What I claim as new, and desire to secure by Letters Patent, is—

1. A case or holder having a closed top, bottom, sides and back, and guides extended along inside the top, bottom and back, combined with a flexible front having a discharge slit or opening intermediate its ends, movable along said guides and of a length sufficient to completely close the box irrespective of the position of the discharge slit or opening, a 45 discharge-roller carried by and moving with said front, a support within the case, and a holder located within the boundaries of the guides, substantially as described.

2. A case or holder having a closed top, bottom, sides and back, combined with a flexible, movable front having a discharge-opening intermediate its ends and extending toward the back inside the top and bottom, a discharge-roller carried by and moving with 55 said front, and a support and holder arranged in the case clear of its bottom and back to allow the front to travel past such support and holder, substantially as described.

In testimony whereof I have hereunto set 60 my hand in the presence of two subscribing witnesses.

JAMES T. HOYT.
